UNITED STATES PATENT OFFICE.

NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN.

BOILER CLEANER.

Application filed February 4, 1924. Serial No. 690,616.

The invention relates to boiler cleaners and refers particularly to that type having a blower element provided with nozzles for discharging cleaning fluid to clean the boiler tubes or other parts of the boiler. Among the objects of the invention is the provision of an improved boiler cleaner of the type mentioned.

With this as well as other objects in view, the invention resides in the novel features of construction and combinations and arrangements of parts as more fully hereinafter set forth.

In the drawings:

Figure 1 is a view partly in longitudinal section through a boiler cleaner embodying my invention, part of the valve control mechanism being shown in full view.

Figures 2 and 3 are respectively cross sections on the lines 2—2 and 3—3 of Figure 1;

Figure 4 is a cross section on the line 4—4 of Figure 3;

Figure 5 is a plan view showing the controlling device of the valve actuating mechanism.

1 is the rotary blower element of the boiler cleaner, and 2 the stationary gooseneck for supplying the cleaning fluid, such as steam or the like, to the blower element. The blower element is rotated by means of a flexible connection such as a chain extending over the sheave wheel 3 which is operatively connected to the pinion 4 meshing with the gear wheel 5 secured upon the blower element.

The blower element comprises the outer tube 6 having a closed inner end and the inner tube 7 concentrically located within the outer tube and having the outwardly extending annular flange 8 abutting the wall of the outer tube. The outer tube is provided with the series of nozzles 9 located inwardly beyond the end of the inner tube and also with the series of nozzles 10 located outwardly beyond the end of the inner tube. The gooseneck 2 has the pair of passages 11 and 12 separated by a wall 11^a, the first of which passages communicates with the inner tube 7 of the blower element through the opening 12^b, and the second of which communicates with the chamber 12^a and thence with the chamber formed between the inner tube 7 and outer tube 6 of the blower element through the openings 13 at the outer

end of the outer tube. 14 and 15 are valves controlling the ports 16 at the lower ends of the passageways 12 and 11 respectively of the gooseneck, the arrangement being such that with the valve in open position, either respective series of nozzles 9 or 10 is discharging cleaning fluid.

The valves are actuated automatically upon the rotation of the blower element 1, and furthermore, the arrangement is such that the valves are alternately moved to open and closed positions. In detail, 17 is a cam at one side of the gear wheel 5 and rotatable therewith, and 18 is a pivotal lever, the upper end of which contacts with the cam 17. This lever is substantially L-shaped and the lower edge thereof near the bend is engageable with the upper surface of the controlling device 19 which is in the form of a disk. This disk is rotatably mounted upon the vertical stem 20 and when depressed by lever 18 is returned to its normal position by means of the coil spring 21 surrounding the stem and abutting the disk and the upper face of the gooseneck at its lower end.

The disk, in its normal position is held out of contact with the gear wheel 5, by means of the abutment of boss 20^a, an integral part of the disk, with the pin 20^b projecting from the stem 20. The disk is provided with the openings 22 which are angularly spaced at equal distances, and also so spaced that when one of the stems of either the valves 14 or 15 registers with an opening, the other stem will register with the solid portion of the disk between the openings, as shown particularly in Figure 5. The disk 19 has a sufficient thickness so that when axially depressed by the lever 18 the valve stem engaging in an opening in the disk will not be depressed, and consequently its valve will remain closed.

However, the valve stem coming into engagement with the solid portion of the disk will be depressed and its valve will be opened against the tension of the coil spring 23 which tends to normally maintain the valve in closed position.

For the purpose of alternately actuating the valves 14 and 15 the controlling disk 19 is provided with the peripheral projections or teeth 24 which are engageable by the radially extending projection or pin 25 upon the gear wheel 5 and which are so spaced that for each revolution of the gear wheel

5 the disk 19 is advanced one tooth and its openings and the solid portions between the openings are successively brought into registration with the valve stems. As a consequence, the valves are alternately moved to open position during the rotation of the blower element. In this connection it is apparent that the length of cam 17 controls the length of time that the valves will remain open or closed.

10 What I claim as my invention is:

1. In a boiler cleaner, the combination with a blower element having a plurality of nozzles arranged in groups for discharging cleaning fluid, of a plurality of reciprocating valves for controlling the discharge of the cleaning fluid through respective groups of said nozzles, and means dependent upon the movement of said blower element for reciprocating said valves.

2. In a boiler cleaner, the combination with a blower element having a plurality of nozzles arranged in groups for discharging cleaning fluid, of means for separately supplying cleaning fluid to each of said groups, a plurality of independently movable valves for controlling said supply means, and means dependent upon the movement of said blower element for moving said valves.

3. In a boiler cleaner, the combination with a blower element having a plurality of nozzles arranged in groups for discharging cleaning fluid, of a plurality of valves for controlling the discharge of the cleaning fluid through respective groups of said nozzles, and means dependent upon the movement of said blower element for actuating said valves, said means including an axially movable and rotatable member.

4. In a boiler cleaner, the combination with a rotary blower element having a plurality of nozzles arranged in groups for discharging cleaning fluid, of means for separately conducting cleaning fluid to each of said groups, a plurality of valves for controlling the passage of cleaning fluid through said conducting means, and means dependent upon the rotation of said blower element for moving said valves from their seats, said means including a single control member.

5. In a boiler cleaner, the combination with a blower element having a plurality of nozzles arranged in groups for discharging cleaning fluid, of a plurality of valves having valve stems for controlling the discharge of the cleaning fluid through respective groups of said nozzles, and means engageable with the stems of the valves dependent

upon movement of said blower element for moving said valves to open position.

6. In a boiler cleaner, the combination with a rotary blower element having a plurality of nozzles arranged in groups for discharging cleaning fluid, of means for separately conducting cleaning fluid to each of said groups, a plurality of valves for controlling the passage of cleaning fluid through said conducting means, and means dependent upon the rotation of said blower element for alternately moving said valves to open position, said means including an axially movable member adapted to be rotated upon rotation of said blower element.

7. In a boiler cleaner, the combination with a blower element having a plurality of nozzles arranged in groups for discharging cleaning fluid, of a tube arranged concentrically within the blower element for conducting cleaning fluid to the nozzles of one of said groups, said inner tube having a portion spaced from the blower element, one of said nozzle groups being in communication with said space, and means for controlling the passage of cleaning fluid within said tube and between the tube and inner walls of the blower element for discharge through said groups of nozzles respectively.

8. In a boiler cleaner, a blower element formed of a pair of concentrically arranged tubes, the outer tube having a plurality of nozzles arranged in groups for discharging cleaning fluid from said tubes, and means for separately supplying cleaning fluid to each of said groups, and means for controlling the supply of the cleaning fluid.

9. In a boiler cleaner, the combination with a blower element having a plurality of nozzles arranged in groups for discharging cleaning fluid, of means including a tube arranged within the said element for separately supplying cleaning fluid to said groups of nozzles, and means dependent upon movement of said blower element for automatically controlling the supply of the cleaning fluid.

10. In a boiler cleaner, a blower element formed of a plurality of concentric cleaning fluid conducting tubes, a nozzle in communication with each tube for discharging cleaning fluid from said tube, a separate conduit for supplying cleaning fluid to each of said tubes, a separate valve controlling the supply of cleaning fluid to each of said conduits, and means for actuating said valves.

In testimony whereof I affix my signature.

NORMAN L. SNOW.
